UNITED STATES PATENT OFFICE.

DONALD F. JOHNSTON, OF TORONTO, ONTARIO, CANADA, ASSIGNOR TO STEWART-WARNER SPEEDOMETER CORPORATION, OF CHICAGO, ILLINOIS, A CORPORATION OF VIRGINIA.

INSTRUMENT-BOARD.

1,305,287.

Specification of Letters Patent. Patented June 3, 1919.

Application filed April 15, 1918. Serial No. 228,547.

To all whom it may concern:

Be it known that I, DONALD F. JOHNSTON, a subject of the Kingdom of Great Britain, residing at Toronto, in the Province of Ontario, in the Dominion of Canada, have invented certain new and useful Improvements in Instrument-Boards, of which the following is a specification, reference being had to the accompanying drawings, forming a part thereof.

The object of this invention is to provide an instrument board applicable to a vehicle body without the use of tools or securing means other than the frictional engagement of certain parts of the board with the vehicle body. It consists in certain features and relations of the parts hereinafter described and shown in the drawings as indicated by the claims.

20 In the drawings:

Figure 1 is a face view of an instrument board embodying this invention together with certain parts of the vehicle body to which it is applied.

25 Fig. 2 is a side elevation partly in section showing the instrument board and related parts on a larger scale.

Fig. 3 is a detail face view of one end of the board and related parts, being taken as indicated at line 3—3 on Fig. 2.

30 Fig. 4 is a detail section taken as indicated at line 4—4 on Fig. 3.

Fig. 5 is a fragmentary view of the end portion of an instrument board embodying a modification of this invention.

35 Fig. 6 is a section taken as indicated at line 6—6 on Fig. 5.

The parts of the vehicle body, shown in the drawings, include the side panels, 1, 40 mounted by the cowl sides, 2, supporting brackets, 3, which carry the wind shield, 4. Extending across the body between the cowl sides, 2, is the instrument board, 5, embodying this invention and having as its primary 45 function the support of the speedometer, 6, or other instrument. The upper edge of the board, 5, is formed with a groove, 7, engaging the depending edge or flange, 8, of the cowl, 9, while the end portions of the 50 board are reduced in thickness and under surfaces are formed convexly to fit the curvature of the downwardly sloping edges, 11, of the cowl sides or brackets, 2, so that the ends of the board will rest and lodge 55 firmly against said parts. The lower edges,

12, of these end portions of the board are wedged into engagement with the short ledges or sills, 13, of the side panels, 1, of the vehicle body. Since the lower edges, 12, are inclined upwardly from the middle portion of the board, they will usually engage only the corner edges, 14, of the sills, 13, as indicated in Fig. 3; but it may be understood that the material of the board, 5, which is preferably wood will be sufficiently 65 elastic and compressible to render this wedging engagement between the lower edge, 12, and the edge, 14, of the side panel, 1, adequate securing for the board by reason of the friction between the parts at these 70 points of engagement.

However, in addition to the friction holding the board in position, it may be noted that the flexible shaft, 15, of the speedometer, trends downwardly in a direction 75 slightly oblique to the plane of the board itself, which is not exactly vertical, and thus the shaft, 15, tends to exert a pull in direction to hold the board in place. Furthermore the weight of the speedometer 80 mechanism in its casing, 16, being principally back of the general plane of the board, and therefore under the board owing to the inclined position of the latter, this weight will also act in a direction to assist the retention of the board in its proper relation 85 to the vehicle body.

It may be further noted that the lower edge of the middle portion of the board at 17 is proximate the inclined steering column, 90 18, which extends at an acute angle to the face of the board, 5, so that if the edges, 12, of the end portions, 10, should become disengaged from the sill edges, 14, the board could not swing upwardly at its lower edge, 95 17, for any considerable distance without encountering the oblique steering column, 18, and being stopped thereby; hence the edges, 12, cannot slide rearwardly upon the sills, 13, for any considerable distance, and, 100 if the board becomes loosened, it must still remain substantially in position in the body. Under all ordinary circumstances, however, the friction at the edges, 14, is sufficient to retain the parts securely with the rear surfaces of the ends, 10, lodged against the curved surfaces, 11, of the brackets, 2.

As a modification of the invention, however, Figs. 5 and 6 present a structure in which the rear faces of the end portions, 10, 110

- of the board, 5, are each provided with flat curved springs, 19, each having one end anchored at or near the upper portion of the width of the board by means of screws, 20, 5 while a clearance groove or notch, 21, is formed near the lower edge, 12, for free play of the end, 22, of each spring, 19. The clearance provided by the groove, 21, will permit the board, 5, to be easily positioned 10 with its groove, 7, engaging the depending cowl flange, 8, but as the reduced end portions, 10, are moved back against the curved edges, 11, of the cowl brackets, 2, the springs, 19, tending to assume as near straight form 15 as possible, will follow along the edges, 14, of sills, 13, strongly engaging the latter and tending to bite into the edges, 14, slightly, so as to resist any reverse movement of the board away from the curved surfaces, 11. 20 In this modification it will be seen that the elasticity of springs, 19, merely replaces the elasticity of the material of the board itself, which is relied upon in the forms shown in Figs. 1 to 4, while the relatively sharp edges, 25 22, of the springs, 19, provide for maximum frictional engagement with the sill edges, 14. It may be noted that the sills, 13, and their edges, 14, are not strictly parallel, but converge forwardly of the vehicle body, while 30 the lower edges, 12, of the ends of the board are oppositely inclined with respect to the upper edge. As a result, in its approach to the final position shown in the drawings, a wider part of the board is constantly presented for engagement in a narrower part 35

of the vehicle body,—narrower both vertically, and horizontally between the sill edges, 14, thus insuring a firm wedging of the board in its place.

I claim:

1. In combination with a vehicle body having a cowl with a depending edge extending transversely of the body and side sills in a plane below said edge, an instrument board wedged in place with its upper 45 edge engaging the cowl edge and with its end portions lodged upon the sills. 2. In combination with a vehicle body having a cowl with a depending edge extending transversely of the body and side 50 sills in a plane below said edge, an instrument board positioned with its upper edge engaging the cowl edge and formed with the end portions of its lower edge oppositely inclined to the upper edge and lodged upon 55 the sills. 3. In the combination set out in claim 2, said sills converging forwardly of the vehicle and said inclined lower edges of the board being wedged into engagement with 60 said converging sills. 4. In the combination set out in claim 1, said end portions of the board being composed of material adapted to react elastically against said sills to produce a frictional engagement therewith. 65

In testimony whereof, I have hereunto set my hand at Toronto, Canada, this 8th day of April, 1918.

DONALD F. JOHNSTON.
